UNITED STATES PATENT OFFICE

154,241

DESIGN FOR A REWINDING DEVICE FOR BANDAGE MATERIAL

Charles Cramer, Gardner, Kans., assignor to The
Cramer Chemical Company, Gardner, Kans., a
corporation of Kansas

Application January 30, 1948, Serial No. 144,177

Term of patent 14 years

(Cl. D41—1)

To all whom it may concern:

Be it known that I, Charles Cramer, a citizen of the United States, residing at Gardner, county of Johnson, and State of Kansas, have invented a new, original, and ornamental Design for a Rewinding Device for Bandage Material, of which the following is a specification, reference being had to the accompanying drawing, forming a part hereof.

In the drawing—

Figure 1 is a perspective view of a rewinding device for bandage material, showing my new design; and

Figures 2 and 3 are views in side elevation, il-

lustrating the opposite sides of said rewinding device, respectively.

I claim:

The ornamental design for a rewinding device for bandage material, substantially as shown.

CHARLES CRAMER.
